By Arthur P. Smith,

Attorney.

UNITED STATES PATENT OFFICE.

FRANK KNOBELOCH, OF DAYTON, OHIO, ASSIGNOR TO THE KINNARD MANUFACTURING COMPANY, OF SAME PLACE.

PAPER BOX.

SPECIFICATION forming part of Letters Patent No. 622,496, dated April 4, 1899.

Application filed June 24, 1898. Serial No. 684,402. (No model.)

To all whom it may concern:

Be it known that I, FRANK KNOBELOCH, a citizen of the United States, and a resident of Dayton, in the county of Montgomery and State of Ohio, have invented certain new and useful Improvements in Paper Boxes, of which the following is a full, clear, and exact description, reference being had to the accompanying drawings.

10 My invention relates to the construction of paper or pasteboard boxes or lids of the kind known as "knockdown," and has for its object to provide a box or lid formed from a single blank of cardboard or other suitable material and which may be easily brought or folded into shape, having at the same time strength and rigidity, the nature of my improvements being more fully hereinafter set forth and described, and shown in the accompanying drawings, which form part of this specification, in which the heavy lines indicate the cut portions of the blank and the dotted lines the scores or creases.

In the drawings, Figure 1 is a plan view of a blank of cardboard or other suitable material cut and scored to be folded into shape and form my improved box or lid. Fig: 2 is a perspective view of the box or lid in process of construction. Fig. 3 is a perspective view 30 of the box or lid complete.

Like letters of reference indicate identical parts in all the figures.

A is the portion of the blank that forms the bottom, B B' the portions that form the sides, and C C' the ends. In order to form the box or lid, the side flaps B' are folded over at the score a onto the side B, where it is preferably glued in place in order to produce a neater appearance, though it need not be glued, if desired. The sides, composed of the side flaps B' and the side B, are then folded up at right angles to the bottom A, as shown in Fig. 2. Integral with the side flaps B' are extensions b b, provided with slits e, which extensions 5 are then bent in at right angles to the sides, as shown in Fig. 2. Intermediate the sides B and ends C are wings c c, which for purposes of appearance and that they may fold into place and at the same time have their edge flush with the edge of the extensions b b are cut in the manner shown in Fig. 1. These

wings are scored diagonally, as shown, to permit of their folding upon themselves. The ends, composed of portions C and C', are then folded up at right angles to the bottom A, 55 and the wings c by reason of the diagonal score are permitted to fold into bellows folds and lie intermediate the end C and the extensions b. If desired, however, the wings c may be cut away from the end C, in which 60 case it will not be necessary to score it diagonally; but it may then be folded in at right angles to the sides in the same manner as the extensions b are folded in. I, however, prefer to leave it integral with the sides and ends 65 and have it scored, as indicated, and fold into bellows folds, as with this construction the corners, which are subject to considerable wear, are greatly reinforced and strengthened. The ends C' are provided with one or more 70 tongues d, which register with and are inserted in the slits e in the extensions b, as shown in Fig. 3. In order to facilitate the insertion of these tongues d in the slits e in the extensions b, I provide an intermediate 75 score in the end flap C'.

By this construction a very strong box or lid is produced, having reënforced sides, ends, and corners, and at the same time one that is neat in appearance. 80

Having thus described my invention, what I claim, and desire to secure by Letters Patent, is—

1. In a "knockdown" box or lid, cut and scored from a blank of cardboard or other suitable material, the combination with bottom, sides, and ends, of wings intermediate the sides and ends, and extensions integral with the sides, said extensions provided with a slit or slits to receive a tongue or tongues 85 integral with the end flaps, substantially as shown and described.

2. In a box or lid, cut and scored from a single blank of cardboard or other suitable material, the combination with bottom, sides, and ends, the sides and ends scored to fold upon themselves, of side extensions and wings integral with the sides, said extensions and wings scored to fold in at right angles to the sides and lie intermediate the overlapped portions of the end flaps, the overlapping portion 95 of the ends provided with tongues registering 100

with slits in the side extensions whereby the sides and ends are locked in position, substantially as shown and described.

3. In a box or lid cut and scored from a single blank of cardboard or other suitable material, the combination with bottom, sides and ends, the sides and ends scored to fold upon themselves, of side extensions and wings, said wings scored to form bellows folds, and to the extensions and wings scored to fold in at right angles to the sides and lie intermediate the overlapping end flaps, said end flaps provided with tongues which enter slits in the side extensions to lock the sides and ends in place, substantially as shown and described.
4. In a knockdown box or lid cut and scored from a single blank of cardboard or other suitable material, the combination with bottom, sides, and ends, of side flaps having side extensions, said extensions having one or more

slits, one or more tongues on the end flaps to be inserted in said slits and lock the sides and ends in place, substantially as and in the manner described.

5. In a box or lid, cut and scored from a single blank of cardboard or other suitable material, the combination with bottom A, sides B, B', B, B', and ends C, C', C, C', the sides B, B', and ends C, C', scored to fold upon themselves, of side extensions b, integral only with side flaps B', and having slits e, and scored to fold in at right angles to the sides, and tongues d, integral with the overlapping end flaps C', said tongues d, registering with the slits e, in the side extensions, substantially as and in the manner described.
